PROCESS FOR PRODUCING ALKALINE EARTH METAL SULFONATES

Manuel Blumer, Petrolia, Pa., assignor to Sonneborn Chemical and Refining Corporation, a corporation of Delaware

No Drawing. Filed Sept. 6, 1956, Ser. No. 608,205

11 Claims. (Cl. 252—33)

This invention is a new and useful process for producing the alkaline earth metal sulfonates of oil-soluble mahogany sulfonic acids in commercially pure form and in systems consisting in part of such sulfonates and in part of hydrocarbon oil. As used herein the term "alkaline earth metal" includes magnesium.

Sulfonic acids are formed when a petroleum distillate is treated with fuming sulfuric acid or sulfur trioxide. A part of these (the so-called green sulfonic acids) together with unconsumed sulfuric acid separate out as a sludge layer, leaving the other sulfonic acids (the so-called mahogany acids) in solution in the acid-treated oil, which also contains as impurities sulfuric acid and sulfur dioxide. These mahogany sulfonic acids are presumably the reaction products of alkyl arenes occurring naturally in the distillate since similar acids result from the treatment of synthetic alkyl arene hydrocarbons with fuming sulfuric acid or sulfur trioxide.

Alkaline earth metal sulfonates of such mahogany sulfonic acids in oil solution can be obtained by neutralizing the sulfonic acids in solution in a hydrocarbon oil with the desired alkaline earth hydroxide or carbonate, provided the concentration of the sulfonic acid is less than 20% and preferably less than 10%.

If the concentration of the mahogany sulfonic acids in the oil solution is above 20%, neutralization with an alkaline earth hydroxide or carbonate produces a viscous reaction mass in which the inorganic impurities, such as calcium sulfate and sulfite, are so finely dispersed as to be a colloidal suspension. Such a reaction mixture cannot be economically filtered or centrifuged to obtain the alkaline earth sulfonates in commercially pure form. It has therefore been found necessary in such case to first produce the alkali metal sulfonates, such as the sodium, ammonium, potassium, etc., which are more easily purified, and thereafter produce the corresponding alkaline earth sulfonates by subjecting the alkali sulfonates so produced to double decomposition, using an inorganic, water-soluble alkaline earth salt.

I have discovered, however, a novel process to convert the mahogany sulfonic acids in solution in a hydrocarbon oil directly to the alkaline earth sulfonates in concentrations of 20% or higher. In those cases in which the concentration of the sulfonic acids in the oil as produced exceeds 40%, additional oil is added to bring the concentration down within the range of 20—40% by weight for reasons which will be hereinafter developed.

Although this oil is preferably added before neutralization, it may be incorporated at any stage prior to separation and recovery of the system, consisting of hydrocarbon oil and alkaline earth sulfonates as hereinafter described.

In accordance with my invention the mahogany sulfonic acids as obtained by acid treatment of a petroleum distillate or a synthetic alkyl arene hydrocarbon are treated with the required quantity of an alkaline earth base in the presence of an alcohol of 1—5 carbon atoms. The alcohol used is of 70—100% concentration, preferably

2

80—90. The alcohol should be sufficient to dissolve the alkaline earth metal sulfonates produced and preferably is by volume from 1—3 times the volume of the mahogany sulfonic acids. Alcohols up to and including 5 carbon atoms can be used, but best results are obtained by using alcohols of 1—3 carbon atoms. The effect of the alcohol in the concentrations specified is to insure that the inorganic impurities resulting from neutralization of the sulfuric acid and sulfur dioxide present, will not be present in solution in the alcohol but, pro contra, will be present as insoluble phases.

It is necessary to have sufficient hydrocarbon oil present in the reaction mixture to act as an agglomerant for the finely divided and dispersed inorganic impurities produced on neutralization, i.e., the alkaline earth sulfates and sulfites. For this purpose, as hereinabove stated, the oil should be present to the extent of from 60—80% of the combined oil plus sulfonic acid, although part of this oil may be incorporated after neutralization. The hydrocarbon oil used can be of widely varying viscosity and specific gravity, such as S.U.S. from 30—1000 seconds at 100° F. and from 0.77—0.95 specific gravity. I have found it best to add the hydrocarbon oil to the mahogany sulfonic acids prior to addition of the alkaline earth base but, as stated, the oil can be added after neutralization provided sufficient time is allowed after addition of the oil for agglomeration and settling out of the agglomerated impurities. If insufficient oil is present the inorganic impurities remain suspended throughout the alcohol in such finely divided form that their separation by filtration or centrifuging is very difficult. When sufficient mineral oil is present it wets the surface of the finely divided inorganic impurities and causes the individual particles to coalesce into larger units which gravity settle as a bottom layer of oil and impurities. To hasten the coagulating effect I have found mechanical stirring satisfactory but other methods of stirring can be used such as, for example, blowing with air. After settling the upper layer consists of the alkaline earth metal sulfonate together with about one-third by weight of the mineral oil in relation to the alkaline earth metal sulfonate. The bottom layer is semi-fluid and will flow at a slow rate but only through a large diameter opening. This layer consists primarily of the inorganic impurities, such as the alkaline earth metal sulfates, sulfites and excess base, slurred by the added mineral oil. Minor quantities of alcohol and alkaline earth metal sulfonates are also present.

Separation of the upper layer and distilling off the alcohol therefrom leaves as a residue the alkaline earth metal sulfonates and mineral oil in commercially pure form. They range from gels to rubbery solids at room temperature but become viscous fluids at temperatures above 200° F.

I have further discovered that alkaline earth metal sulfonate oil systems of the type described, which are fluid at room temperature and characterized by much lower viscosities throughout the entire range, may be produced by incorporating small percentages of a water or alcohol soluble salt of an alkaline earth metal into the alkaline earth sulfonate, either prior to distilling off the alcohol or even to the residue from the alcohol recovery. It is preferably added as a water or alcohol solution and the solvent then removed by any known process to solubilize the salt into the alkaline earth metal sulfonate systems.

I have successfully used alkaline earth metal chlorides, nitrates, acetates, formates, but other water-soluble or alcohol-soluble salts can also be used.

If a basic alkaline earth metal sulfonate is desired, the alkaline earth metal base can be added either alone or in combination with the alkaline earth salt, to obtain

a basic alkaline earth metal sulfonate of satisfactory fluidity at both ambient and elevated temperatures. This effect is illustrated in the following example:

Example 1

The mahogany sulfonic acids used had the following tests:

Oil-soluble sulfonic acids	percent	50.7
Mineral Oil	do	35.5
Water	do	3.0
Free sulfuric acid	do	10.3
Sulfur dioxide	do	0.5
Molecular weight		425

To the above sulfonic acids I added 25% by volume of a mineral oil distillate of the following tests:

API gravity	36.0
S.U.S. vis/100	sec 65
Flash point	° F 360
Color—NPA	2 minus

I prepared the calcium sulfonate by my invention as follows:

500 ml. of 80% isopropyl alcohol was mixed with 50 g. calcium hydroxide (hydrated lime). The mixture was stirred mechanically and to the stirred mixture I added a solution consisting of about 200 g. of the above mahogany sulfonic acid and about 50 g. of the mineral oil.

The acids reacted with the calcium hydroxide to form the calcium sulfonate. The quantity of oil used was found sufficient for the agglomeration and settling of the impurities, but more mineral oil can be added for this purpose if found necessary.

After separation of phases by settling, although centrifuging can also be used, the upper alcohol solution of the purified calcium sulfonate was distilled to remove the alcohol and dehydrated to remove water. I obtained a product of the following composition:

Percent Calcium sulfonate	65
Percent Mineral oil	35
Percent Sulfated ash	13.95
Alkalinity	0
Molecular weight	880

Physical form, gel at 80° F., viscous fluid at 200° F.

Example 2

To improve the fluidity of the above calcium sulfonate-oil system, I added small percentages of calcium chloride in the form of a 20% aqueous solution to an alcohol solution of calcium sulfonate so produced prior to removal of alcohol by distillation. The calcium sulfonate was diluted with mineral oil to a 40% concentration. Upon distillation of the alcohol and dehydration to remove water, I obtained the following products:

Percent Calcium Chloride added	Percent Sulfated Ash	Fluidity	
		80° F.	S.U.S. Vis 210
0	8.60	gel	too viscous to determine.
1.0	9.62	viscous fluid	1268 sec.
2.0	10.50	fluid	664 sec.
5.0	12.90	do	218 sec.

This demonstrates that small percentages of calcium chloride change the gel structure of the calcium sulfonate system to that of a fluid of low viscosity. Similar results were obtained by the use of calcium formate, acetate and nitrate.

When excess lime is added together with the calcium chloride to obtain a basic fluid calcium sulfonate, it is necessary to filter the product after distillation and dehydration to remove unreacted lime and other impurities.

The basic calcium sulfonate thus obtained tested as follows:

Percent Calcium sulfonate	40.0
Percent Calcium hydroxide	1.5
Percent Calcium chloride	1.0
Percent Mineral oil	57.5
Percent Sulfated ash	10.8
Molecular weight	880
S.U.S. Viscosity at 210° F.	380
Alkalinity—mg. KOH/g.	20.0

The above shows that this invention may be employed to produce a basic calcium sulfonate system free from undesirable inorganic impurities, of satisfactory fluidity and possessing the desired basicity.

Other alkaline earth metal sulfonates, similar to the calcium sulfonate described above, can be prepared by using the appropriate alkaline earth base in place of calcium hydroxide.

Example 3

I formed a slurry of 82 g. of strontium hydroxide in 500 ml. of 80% isopropyl alcohol. I also added 1½ g. strontium chloride in aqueous solution. To this I added sufficient of the crude sulfonic acids and mineral oil, referred to in Example 1 above to obtain a neutral solution of strontium sulfonate. A purified neutral sulfonate was obtained upon removal of the alcohol and water.

In a second experiment I added another 82 g. of strontium hydroxide to neutral strontium sulfonate so prepared after removal of the alcohol and before dehydration. After filtration to remove excess hydroxide and other inorganic impurities, I obtained the following:

Test	Neutral Strontium Sulfonate	Basic Strontium Sulfonate
Percent sulfonates	50.0	45.0
Percent oil	49.0	41.7
Percent strontium chloride	1.0	1.0
Percent strontium hydroxide	0	12.3
Percent sulfated ash	11.3	28.7
Alkalinity	0	113 mg. KOH/g.
Molecular Weight	927	927
Physical Form	fluid	thin fluid

Similar results were obtained by using other strontium water-soluble salts in place of the chloride.

Example 4

In this experiment I used 115 g. of barium hydroxide suspended in 500 ml. of 80% isopropyl alcohol. I also added 2.1 g. barium chloride in aqueous solution. I then added the proper quantity of mahogany sulfonic acids to neutralize the base, and sufficient mineral oil to agglomerate the barium sulfate and sulfite formed as impurities, as described previously. A purified neutral barium sulfonate is obtained from the settled alcohol solution.

I also made the basic barium sulfonate by adding an equal quantity of barium hydroxide, in water solution, to the neutral barium sulfonate produced as given above, after the alcohol was removed but prior to dehydration. The finished product requires a filtration to remove the last traces of insoluble impurities.

I obtained the following barium sulfonates by the use of this process:

Test	Neutral Barium Sulfonate	Basic Barium Sulfonate
Percent sulfonates	50.0	46.1
Percent oil	49.0	44.0
Percent barium chloride	1.0	1.0
Percent barium hydroxide	0	8.9
Percent sulfated ash	12.1	21.7
Alkalinity	0	58 mg. KOH/g.
Molecular weight	977	977
Physical form	fluid	thin fluid

Similar results were obtained by the use of water-soluble barium salts in place of the chloride.

Example 5

I prepared the magnesium sulfonate, using magnesium hydroxide for neutralizing the mahogany sulfonic acids and magnesium chloride for reducing the viscosity of the neutral magnesium sulfonate.

The neutral magnesium sulfonate tested as follows:

Percent magnesium sulfonate	50.0
Percent magnesium chloride	1.0
Percent magnesium hydroxide	0
Percent oil	49.0
Percent sulfated ash	8.17
Alkalinity	0
Molecular weight	864
Physical form	fluid

I claim:

1. Process for the production of commercially pure alkaline earth metal sulfonates in mixture with hydrocarbon oil which comprises reacting a mahogany sulfonic acid containing in excess of 20% of sulfonic acid in relation to the total sulfonic acid and hydrocarbon oil and containing free sulfuric acid and sulfur dioxide, said mahogany sulfonic acid being produced by the sulfonation of alkyl aromatics of the type contained in petroleum distillates, with an amount of an alkaline earth base sufficient to at least neutralize said sulfonic acid in the presence of an amount of alcohol of not more than 3 times the volume of the mahogany sulfonic acid but sufficient to dissolve the alkaline earth metal sulfonates produced, said alcohol having not more than 5 carbon atoms in its molecule and a concentration of at least 70% the balance being water, thereby producing alkaline earth metal sulfonates in alcohol solution and settling said alkaline earth metal sulfonates in said alcohol solution in the presence of hydrocarbon oil having a viscosity S.U.S. of 30 to 1000 seconds at 100° F. and a specific gravity of from 0.77 to 0.95 to the extent of 60-80% by weight based on the combined oil and sulfonic acid thereby producing an alcohol phase containing in solution the alkaline earth metal sulfonate and some of the hydrocarbon oil, and as a separate phase, oil and oil-agglomerated impurities and recovering a mixture of oil and alkaline earth metal sulfonate from the alcohol phase.

2. Process according to claim 1 in which the alcohol is isopropyl alcohol.

3. Process according to claim 1 in which the alkaline earth metal sulfonate produced is calcium sulfonate.

4. Process according to claim 1 in which prior to recovery of the mixture comprising oil and alkaline earth metal sulfonates from the alcohol phase there is incorporated therein at least 1% by weight, based on the weight of the mixture of an alkaline earth metal salt selected from the water-soluble and alcohol-soluble salts.

5. Process according to claim 4 in which the alkaline earth metal sulfonate produced is calcium sulfonate.

6. Process for the production of commercially pure alkaline earth metal sulfonates in mixture with hydrocarbon oil which comprises reacting a mahogany sulfonic

acid containing in excess of 20% of sulfonic acid in relation to the total sulfonic acid and hydrocarbon oil and containing free sulfuric acid and sulfur dioxide, said mahogany sulfonic acid being produced by the sulfonation of alkyl aromatics of the type contained in petroleum distillates, with an amount of an alkaline earth base sufficient to at least neutralize said sulfonic acid in the presence of an amount of alcohol of not more than 3 times the volume of the mahogany sulfonic acid but sufficient to dissolve the alkaline earth metal sulfonates produced, said alcohol having not more than 5 carbon atoms in its molecule and a concentration of at least 70% the balance being water, and in the additional presence of hydrocarbon oil having a viscosity S.U.S. of 30 to 1000 seconds at 100° F. and a specific gravity of from 0.77 to 0.95 to the extent of 60-80% by weight based on the combined oil and sulfonic acid thereby producing alkaline earth metal sulfonates in alcohol solution and settling said alkaline earth metal sulfonates in said alcohol solution thereby producing an alcohol phase containing in solution the alkaline earth metal sulfonate and some of the hydrocarbon oil, and as a separate phase, oil and oil-agglomerated impurities and recovering a mixture of oil and alkaline earth metal sulfonate from the alcohol phase.

7. Process according to claim 6 in which the alcohol is isopropyl alcohol.

8. Process according to claim 6 in which the alkaline earth metal sulfonate produced is calcium sulfonate.

9. Process according to claim 6 in which the mixture contains from about 20 to 40% of sulfonic acids in relation to the total sulfonic acid plus hydrocarbon oil.

10. Process according to claim 6 in which prior to recovery of the mixture comprising oil and alkaline earth metal sulfonates from the alcohol phase, there is incorporated therein at least 1% by weight, based on the weight of the mixture of an alkaline earth metal salt selected from the water-soluble and alcohol-soluble salts.

11. Process according to claim 10 in which the alkaline earth metal sulfonate produced is calcium sulfonate.
